UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed June 3, 1929. Serial No. 367,894.

This invention relates to mining machines and more particularly, but not exclusively, pertains to coal mining machines of the flexibly fed, continuous cutter type.

An object of this invention is to provide an improved coal mining machine. Another object is to provide an improved coal mining machine of the flexibly fed, continuous cutter type having improved feeding and guiding mechanism. A further object is to provide an improved bottom cutting mining machine of the room and pillar type having improved machine feeding and guiding mechanism wherein separate relatively rotatable feeding and controlling members and separate flexible feeding elements cooperating respectively therewith are employed for feeding and guiding the machine along the coal face. Still another object is to provide in a machine of the aforesaid type improved motor driven plural speed transmission connections for each of the feeding and controlling members whereby the latter may be rotated either separately or simultaneously in a direction to draw in their respective flexible feeding elements at a relatively slow cutting speed or at a relatively high machine moving speed. It is also an object of this invention to provide in a mining machine of the aforesaid type improved driving and controlling means for the feed operating and controlling members whereby said members may rotate in a direction to pay out said flexible feeding elements under various degrees of operator-controlled frictional resistance, or to permit said members to rotate freely in a direction to pay out said flexible feeding elements. Another object is to provide in a mining machine of the aforesaid type improved feeding mechanism including relatively rotatable winding drums mounted in an improved manner on the machine and having separate plural speed driving connections whereby the feed drums may be rotated in winding direction either at the same time or separately at a plurality of predetermined speeds. Yet another object is to provide improved guiding means for the flexible feeding means of a flexibly fed coal mining machine. Still another object is to provide an improved coal mining machine of

the room and pillar "lowvein" type which is exceedingly low in height. Another object is to provide an improved "lowvein" room and pillar mining machine having improved feeding and cutting mechanisms driven respectively from opposite ends of a low compact horizontal motor arranged between the feeding and cutting mechanisms, the parts being so arranged and constructed as to make the machine extremely compact, both vertically and laterally without increasing the overall dimension of the machine. These and other objects and advantages of this invention will, however, be clearly apparent from the following description and as more particularly pointed out in the appended claims.

In the accompanying drawings there is shown for purposes of illustration one form which the invention may assume in practice.

In these drawings,—

Fig. 1 is a top plan view of the illustrative embodiment of the improved mining machine, the cutter bar being broken away and the arrangement of the feed cables when cutting from left to right being indicated by dotted lines.

Fig. 2 is a side elevational view of the machine shown in Fig. 1.

Fig. 3 is a rear end elevational view of the improved mining machine.

Fig. 4 is a central longitudinally extending vertical sectional view taken substantially on line 4—4 of Fig. 1.

Fig. 5 is a horizontal sectional view taken substantially on line 5—5 of Fig. 2.

Fig. 6 is a vertical longitudinally extending sectional view taken substantially on line 6—6 of Fig. 5.

Fig. 7 is a detail sectional view taken on line 7—7 of Fig. 5.

Fig. 8 is a transverse vertical sectional view taken substantially on line 8—8 of Fig. 6.

Fig. 9 is a longitudinally extending vertical sectional view taken substantially on line 9—9 of Fig. 5.

Fig. 10 is a detail view illustrating the improved operating mechanism for the feed controlling clutches.

Fig. 11 is a detail sectional view taken on line 11—11 of Fig. 10.

Fig. 12 is a detail view illustrating the front swing arm and pivoted guide for the feed cable.

Fig. 13 is a detail sectional view taken on line 13—13 of Fig. 12.

In this illustrative construction there is shown a mining machine of the flexibly fed, "lowvein", continuous cutter type of an exceedingly low compact design especially adapted to use in cutting low coal in accordance with the room and pillar system of mining, although it is obvious that various features of the invention may be employed in coal mining machines of various other types. The improved mining machine generally comprises a low compact machine frame 1 of generally rectangular shape having a smooth plane bottom surface 2 upon which the machine is adapted to rest upon and slide in any direction over the mine floor. The machine frame 1 comprises a central motor section 3 mounted upon a bed section 4 and interposed between the feed and cutter sections 5 and 6 respectively. The frame sections 3, 4, 5 and 6 are rigidly secured together in any appropriate manner and when united form a machine body providing a rigid flat frame or shoe upon which the various mechanisms of the machine are supported. Rigidly secured to the cutter frame section 5 and projecting forwardly lengthwise of the machine frame is a horizontal plane cutter bar 7 carrying on its margin an orbitally movable cutter bit carrying cutter chain 8. The machine is adapted to be propelled bodily laterally transversely across the coal face and guided during such feeding by flexible feeding means including advance and receding flexible feeding and controlling elements 9 and 10 cooperating respectively with relatively rotatable feed operating and controlling members 11 and 12 arranged on transverse axes at the rear end of the machine on opposite sides of the latter, the flexible feeding means and feed operating and controlling members herein being in the form of separate cables or ropes cooperating with winding drums. The cable 10 is wound about the winding drum 12 in a direction opposite from that which the cable 9 is wound on the drum 11 but as these drums are driven in opposite directions, the cables are both drawn in by power. The central motor section 3 of the machine frame houses a horizontal motor 13 adapted to drive the feeding and cutting mechanisms in either of opposite directions and which may be of the reversible electric type, of a low compact design having its power shaft horizontally disposed and extending longitudinally of the machine.

The cutting mechanism, as shown in the drawings, specifically comprises a bevel pinion 14 suitably fixed to the forward end of

the motor shaft and meshing with a bevel gear 15 herein formed integral with the vertical shaft 16. This shaft 16 is suitably journaled in ball bearings 17 and has also formed integral therewith a spur pinion 18 meshing with a larger spur gear 19. The spur gear 19 has a depending hub portion 20 journaled on ball bearings 21 surrounding and supported by a vertical stud 22. As shown, the stud 22 is threadedly connected at its opposite ends as at 23 to detachable cap members 24 and 25 respectively suitably bolted to the cutter frame section 6. The depending sleeve portion 20 of the gear 19 is connected by a semi-permanent clutch 26 to a clutch member 27 having external clutch teeth 28 and a hub portion 29 surrounding the stud 22. Rotatably mounted on this hub 29 is a similar clutch member 30 connected as by a semi-permanent clutch 31 to the hub of a cutter chain drive sprocket 32. This cutter chain drive sprocket 32 is rotatably mounted on ball bearings 33 surrounding and supported by the vertical stud 22. The hub 29 of the clutch member 28 is interposed between the lower bearing 21 for the gear 19 and the upper bearing 33 for the sprocket 32. The bearings 33 and the sprocket 32 are maintained in operative relation by means of a cup-shaped member or step bearing 34 in turn held in position by a detachable bottom plate 35. The frame section 6 is provided with a depending cylindrical portion 36 having formed therein a bore 37 within which is vertically reciprocable a cylindrical clutch shipper member 38 connected to a clutch member 39 having internal clutch teeth adapted to cooperate with the teeth on the clutch members 27 and 30. As shown in Fig. 4 the clutch shipper member 38 is adapted to be shifted axially by means of a lever 40 pivotally mounted at 41 in a suitable manner within the cutter frame section and connected at 42 to the clutch shipper member. The other end of this lever is pivotally connected at 43 to a link 44 in turn pivotally connected at 45 to an arm 46. This arm is suitably fixed to a horizontal shaft 47 extending transversely of the machine and having secured thereto at its opposite ends suitable control handles 48 (see Figs. 1 and 2). As illustrated the cutter bar 7 has formed thereon an upstanding annular portion 49 mounted on the depending portion 36 of the cutter frame section and rigidly fixed to the cutter frame by screws 50. The lower portion of the cutter bar has an annular bottom support 51 surrounding and supported by the step-plate 34. It will be evident that when the clutch member 39 is in the position shown in Fig. 4 the clutch members 27 and 30 are connected and as a result the cutter chain driving sprocket 32 is connected in driving relation with the motor. The cutter chain drive sprocket may be disconnected from the mo-

tor by simply shifting the member 38 upwardly to disconnect the clutch teeth on the member 39 from the teeth on the clutch member 30.

5 In this illustrative embodiment of the invention improved separate plural speed driving connections are provided between the motor 13 and the winding drums 11 and 12 whereby the latter may be rotated in winding 10 direction either separately or simultaneously at a relatively low cutting speed or at a relatively high machine moving speed, or may rotate in unwinding direction under various degrees of frictional resistance or freely. As 15 shown in Figs. 5, 6, 8, and 9 these improved driving connections comprise a spur pinion 52 rigidly secured as by a key and screw connection 53 to the rear end of the motor shaft. This pinion 52 meshes with a spur gear 54 20 journaled on ball bearings 55 supported by a horizontal longitudinally extending stud shaft 56 disposed parallel with and in a plane below the motor shaft and suitably rigidly fixed within the feed frame section 5. The 25 spur gear 54 meshes with spur gears 57 and 58 suitably rigidly secured as by keys 59 to horizontal shafts 60 and 61 respectively disposed on horizontal longitudinally extending axes spaced equi-distantly from the longitudinal 30 vertical center of the machine. These shafts are journaled within the lower part of the feed frame section within ball bearings 62 and 63. The slow speed driving connections for the winding drums 11 and 12 comprise 35 worms 64 and 65 herein having teeth of the same lead and direction and meshing respectively with worm wheels 66 and 67. As clearly shown in Fig. 8, these worm wheels are fixed at 68, as by keying, to vertical shafts 69 40 and 70 respectively disposed at opposite sides of the feed frame section, these worm wheels meshing with the worms 64 and 65 at the opposite sides thereof and they are thereby driven at the same speed in opposite directions. The shafts 69 and 70 are journaled at 45 their upper and lower ends within ball bearings 71 and 72 respectively, suitably supported within the feed frame section. Secured to the vertical shafts 69 and 70 respectively are worms 73 and 74 having teeth of the same lead and direction and meshing respectively with worm wheels 75 and 76. These worm wheels 75 and 76 are journaled on ball bearings 77 and 78 respectively, supported by transversely extending horizontal 55 shafts 79 and 80 as clearly shown in Fig. 5 and are respectively connectible to these shafts by means of friction clutches 81 and 82. As the friction clutches within the worm 60 wheels 75 and 76 are substantially identical in construction, the description of one will suffice for both. Referring more particularly to the friction clutch 81 within the worm wheel 75, it will be observed that the same 65 comprises a series of clutch plates 83 car-

ried by the worm wheel and interleaved with a series of clutch plates 84 carried by a clutch member 85 keyed at 86 to the shaft 79. This clutch member 85 surrounds the shaft 79 and forms a support for the ball bearing 77 on 70 which the worm wheel is journaled, the ball bearings 78 being supported directly on the shaft. The operating means for the friction clutches 81 and 82 will be later described. As illustrated, the transverse shafts 79 and 80 are arranged in axial alinement at the rear end of the machine frame and are journaled at their outer ends within ball bearings 86 supported by the sides of the feed frame section. The inner adjacent ends of the shafts 79 and 80 are journaled within ball bearings 87. Herein formed integral with the outer ends of the shafts 79 and 80 respectively, are spur gears 88 and 89 meshing with internal gears 90 and 91 respectively, herein formed 85 integral with the winding drums 11 and 12. The winding drums 11 and 12 are each journaled on ball bearings 92, 93 supported on a laterally projecting stub shaft 94 secured by screws 94^a to the opposite sides of the feed 90 frame section, the stub shafts 94 being, if desired, coaxially arranged and disposed parallel with and slightly in front of the alined transverse shafts 79 and 80. Each of these winding drums is composed of two parts secured together by screws 95 and suitable dowel pins and is held from axial displacement from the stub shaft by means of a two-part or split sleeve 96 surrounding a reduced portion 97 on the stub shaft and engaging the 100 inner races of the ball bearings 92 and 93. This two-part sleeve is held in place by a retaining sleeve 98, and the complete bearing structure for each drum is disposed in a bore 99 within the drum. Secured to the opposite 105 sides of the feed frame section by bolts 100 are plates 101 each having an annular flanged portion 102 encircling the outer periphery of the internal gears 90 and 91 respectively, carried by the winding drums. These flanged 110 portions 102 each carry packing rings 103 engaging the outer periphery of the internal gears and thereby preventing access of dirt or other foreign substances into the internal mechanism. 115

It will thus be seen that when the clutch 81 within the worm wheel 75 is applied, the winding drum 11 may be driven from the motor at a relatively slow speed through pinion 52, spur gears 54, 57, shaft 60, worm 64, worm wheel 66, vertical shaft 69, worm 73, worm wheel 75, clutch plates 83 and 84, shaft 79, and spur gear 88 meshing with internal gear 90 carried by the winding drum 11. When the clutch 82 within the worm wheel 76 is applied the winding drum 12 may be driven in the opposite direction at a relatively slow speed through a similar train of gearing. It will also be seen that the friction clutches may be sufficiently released to 120 125 130

permit the cables to unwind from the drums under various degrees of frictional resistance under the control of the clutch operating mechanism. Upon release of the friction clutches the drums may be entirely relieved from any frictional resistance due to the action of the friction clutches.

The fast speed driving connections for the winding drums 11 and 12 comprise worms 105 and 106 having oppositely inclined teeth of the same lead and suitably rigidly fixed to the shafts 60 and 61 respectively, as clearly shown in Figs. 6 and 9. These worms 105 and 106 mesh respectively with worm wheels 107 and 108 journaled at their adjacent sides within ball bearings 109 supported within a centrally disposed bearing bracket 110 in turn suitably supported within the feed frame section 5. These worm wheels are journaled at their opposite or remote sides within ball bearings 111 supported by the shafts 79 and 80. As clearly shown in Fig. 5, the adjacent hub portions of these worm wheels 107 and 108 form supports for the ball bearings 87 within which the inner adjacent ends of the shafts 79 and 80 are journaled. These worm wheels are connectible to the shafts 79 and 80 respectively by means of friction clutches 112, 113. These clutches each comprise a series of clutch plates 114 carried by the worm wheel and interleaved with a corresponding series of clutch plates 115 carried by a clutch member 116 keyed at 117 to its respective shaft. The operating means for the friction clutches 112 and 113 will hereinafter be described.

From the foregoing description it will be evident that when the friction clutch 112 is applied the winding drum 11 may be driven from the motor at a relatively high speed through spur pinion 52, gears 54, 57, shaft 60, worm 105, worm wheel 107, shaft 79, and spur gear 88 meshing with the internal gear 90 secured to the winding drum 11. The winding drum 12 may be driven from the motor at a relatively fast speed in the opposite direction through a similar train of gearing upon suitable application of the friction clutch 113.

The operating mechanism for the fast and slow speed control clutches 112, 81 and 113, 82, for the winding drums 11 and 12 respectively, will now be described. Surrounding the shafts 79 and 80 and interposed between the worm wheels 75, 107 and 76, 108 respectively, are clutch applying members 119, 120. Each of these clutch applying members has interposed therebetween and its respective clutch plates, suitable thrust bearings 121. Engaging a peripheral groove on each of the clutch members 119, 120 is a shipper yoke 123 pivotally connected at 124 within the feed frame section. Connected to each of the shipper yokes 123 is a trunnion 125 threadedly connected at 126 to a threaded portion

127 on a hollow shaft 128. The shafts 128 are horizontally disposed and extend transversely of the machine in the rear of and slightly above the alined shafts 79 and 80. These shafts are journaled at their outer ends in ball bearings 129 suitably supported within the sides of the feed frame section and have formed thereon clutch teeth 130 with which clutch teeth 131 formed on an operating lever 132 are adapted to cooperate. The operating lever 132 is connected by a pin 133 to one end of a rod 134 extending transversely across the machine centrally through the shafts 128. Secured by a pin 135 to the opposite end of the rod 134 is a similar operating lever 136. This rod 134 carries at one end a spring pressed plunger 137 which is engageable with spaced grooves 138 formed within one of the shafts 128 and this plunger and these grooves cooperate to lock the operating rod 134 in its different adjusted positions. It will thus be seen that when the lever 132 is shoved inwardly the clutch teeth 130 and 131 are connected while the clutch teeth on the lever 136 and the other shaft 128 are disconnected. Upon rotation of the lever 132 when so positioned the shaft 128 is rotated, thereby moving the trunnion nut 125 axially relative to the shaft, swinging the shipper yoke 123 about its pivot and applying one or the other of the friction clutches 81, 112 within the worm wheels 75 and 107 respectively. It will also be evident that when the lever 136 is shoved inwardly and connected to the adjacent shaft 128, the operating means for the clutches 82 and 113 may be actuated.

As illustrated, alined with the shaft 61 and clutched thereto at 140 is a shaft 141. The shaft 141 is journaled at its forward end within an adjacent ball bearing 63 for the shaft 61 while the rearward end of the shaft 141 is journaled in a ball bearing 142 suitably supported within the feed frame section. Secured to the shaft 141 is a worm 143 meshing with a worm wheel 144 keyed at 145 to a vertical shaft 146. This shaft is journaled in ball bearings 147 suitably supported by the feed frame section and has keyed thereto at its upper end at 148 a spur gear 149 which herein constitutes the final truck driving gear on the machine. This spur gear is adapted to mesh with a truck driving gear on a transport truck in a well known manner, the mining machine being adapted to be supported upon and drive the wheels of the truck. It will thus be seen that when the machine is being propelled about the mine while mounted on its transport truck the motor 13 of the machine is adapted to drive the truck wheels through pinion 52, gears 54, 58, shaft 61, worm 143, worm gear 144, vertical shaft 146, and spur gear 149.

Improved guiding means are also employed for guiding the feed cables 9 and 10 dur-

ing the different operations of the machine. Secured to the opposite sides of the cutter frame section at the forward end of the machine are guide sheaves 150 and 151. An improved adjustable mounting is provided for each of these guide sheaves which herein comprises a support member 152 having a bifurcated outer end supporting a stud 153 on which the guide sheave is journaled. The inner end of this support 152 is provided with a cylindrical portion 154 rotatably mounted within a bore 155 formed within the lower end of a pivoted swing arm 156. The arm 156 is pivotally connected at 157 to a bracket 158 secured by a screw 159 to the side of the frame. A suitable releasable locking pin 160 is employed for holding the swing arm 156 in the position shown in Fig. 12, it being obvious that when the locking pin 160 is released the guide sheave carried thereby may be swung upwardly over the top of the machine in its "out of the way" position. The pivoted support member 152 is held in position within the lower end of the swing arm 156 by means of a pin 161 which, when the support 152 is swung into a position wherein the sheave is disposed in a vertical plane, may enter a groove 162 in the swing arm thereby permitting axial release of the bearing support 154 from the bore 155. It will also be noted that the support 152 has a central bore 163 and a communicating lateral slot 164. When the support is released from the swing arm 156 the feed cable may be passed through the bore 155 in the swing arm and reeved about the guide sheave, the support 152 thereafter being inserted and locked within the bore 155. The support 152 is adapted to rotate within the lower end of the swing arm to position the guide sheave at various angles thereby permitting the feed cable to be extended laterally at various angles from the side of the machine. At opposite sides of the rear end of the machine frame there are provided sets of guide sheaves 165, 166 and 167, 168. As the mountings for these sets of guide sheaves are identical, the description of the mounting for the set of guide sheaves 165 and 166 will suffice for both. Referring more particularly to Fig. 7 it will be noted that the guide sheave 165 is journaled on a bearing sleeve 169 supported by a vertical stud 170 carried by the feed frame section. Also pivotally mounted on the stud 170 is a horizontal swing arm 171 carrying at its outer end a hollow stud 172 supporting a bearing sleeve 173 on which the guide sheave 166 is journaled. The swing arm 171 is adapted to be swung outwardly as indicated in dotted lines in Fig. 1 and inwardly to the full line position shown in Figs. 1 and 5 and locked in this latter position by means of a vertical spring pressed locking pin 174 and a locking aperture 175 formed in the frame of the machine. This locking pin is provided at its upper end with a knob 176 by means of which the pin may be manually lifted out of engagement with the locking aperture to release the swing arm from the frame. As shown in Fig. 5 each of the swing arms 171 is provided with an abutment surface 177 which is engageable when the arm is in its extreme outer position with an abutment surface 178 formed on the feed frame section. When the parts are in the position shown in Fig. 1, that is, when the machine is cutting from right to left, the feed cable 9 extends from the bottom of the feed drum 11 forwardly along the side of the machine, through the passage 163 in the bearing support 154 and around the sheave 150 laterally from the forward end of the machine frame. The receding or controlling cable 10 extends from the bottom of the controlling drum 12 rearwardly past the guide sheave 167 and around the guide sheave 168 laterally from the rear end of the machine frame. When the machine is cutting from left to right the cables 9 and 10 are reversely wound on their respective drums and cable 10 is passed around the front guide sheave 151 and the cable 9 is passed about the rear guide sheaves 165 and 166, as indicated in dotted lines in Fig. 1. If desired the guide sheave 150, 151 which is not in use may be swung up out of the way against the side of the machine frame.

The operation of the improved mining machine is as follows. The machine is propelled about the mine while mounted on its transport truck, the truck wheels being driven from the driving motor 13 of the machine. When the working place is reached, the machine is unloaded from the truck in a well known manner. If it is desired to cut from right to left, the cable 10 is extended from the winding drum 12 rearwardly around guide sheave 168 and then forwardly along the side of the machine and around the front guide sheave 151 to a suitable anchor or roof jack disposed at the right hand rib. The operator then swings the lever 136 in the proper direction to rotate the shaft 128 in a direction to swing the shipper yoke 123 about its pivot thereby to apply the friction clutch 113 within the fast speed worm wheel 108, and as a result the winding drum 12 is driven from the motor 13 at a relatively high machine moving speed winding in the cable 10 and sliding the machine bodily over the mine bottom to a position adjacent the face at the right hand rib, the friction clutch 113 thereafter being released. The other feed cable 9 on the drum 11 may be used during this machine moving operation or if desired both cables may be used. After the machine is suitably positioned adjacent the coal face the cable 10 is disconnected from the guide sheave 151 while still retaining its connection with the jack at the right hand rib and the

advance feeding cable 9 is extended from the feed drum 11 forwardly along the advancing side of the machine and around guide sheave 150 laterally from the machine to a suitable 5 anchor or roof jack disposed at the left hand rib adjacent the coal face. The operator then swings the cutter chain clutch control lever 48 in a direction to shift the clutch member 39 in a position to connect the cutter chain 10 drive sprocket to the motor thereby rapidly circulating the cutter chain about the cutter bar. The friction clutch 82 within the slow speed worm wheel 76 is then applied and the winding drum 12 is rotated at a slow cutting 15 speed, winding in the cable 10 and moving the machine bodily in a forward direction, thereby sumping the cutter bar longitudinally beneath the coal, the winding drum 11 maintaining the advance feed cable 9 under tension under control of friction clutch 81 20 thereby guiding the machine during its sumping movement. It will be noted that if desired the cutter bar may be sumped beneath the coal by means of the feed cable 9 and winding drum 11, or if desired both the cables 9 and 10 may be simultaneously wound in to sump in the cutter bar. The slow speed clutch 81 within the slow speed worm wheel 75 is then applied and the winding drum 11 25 is rotated at a slow speed drawing in the advance feed cable 9 thereby straightening up the machine and feeding the machine bodily laterally transversely across the face of the coal. During the transverse cutting operation the receding or controlling cable 10 is paid out by the controlling drum 12 under frictional resistance, the drum 12 tending to wind in the cable 10 at a slow speed, but due to the opposing forces tending to move the 30 rear end of the machine forwardly, the friction drive clutch for the drum slipping sufficiently to permit the unwinding of the cable. It will further be evident that the drum 12 may be rotated in winding direction at a relatively 35 low speed or at a high speed at will to effect movement of the rear end of the machine rearwardly to angle the cutter bar relative to the coal face. The forward end of the machine may be swung forward upon application 40 of the fast speed drive clutch for the feed drum 11 or slowing down or interrupting paying out of cable 10. It will also be noted that the rear end of the machine may be swung forward by releasing the friction clutch controlling the drum 12 thereby permitting the drum 12 to unwind freely, the pull of the feed cable 9 on the forward end 45 of the machine causing the machine to swing. At the end of the transverse cut the feed drum 50 11 is rotated in winding direction at a relatively high speed and the cutter bar is angled relative to the coal face in a well known manner. The cables are then disconnected from their jacks and the feed cable 9 is extended to 55 an anchor or roof jack at the rear end of the

machine and the drum 11 is rotated in a winding direction at a slow speed and the cutter bar withdrawn from beneath the coal. If desired the cable 10 and drum 12 may be used to retract the machine from the face. One or the other of the cables 9, 10 is then extended to a jack near the transport truck and the cable is wound in at a fast machine moving speed thereby hauling the machine over the mine floor and onto its transport truck. The truck is then propelled along the mine track-way by the mining machine motor 13 through the truck driving gear on the machine to another working place. When it is desired to operate the machine to cut from left to right it is evident that the motor may be reversed, the cutter bits turned in their respective links, and the cables re-wound on their respective drums. These and other operations of the improved mining machine will be clearly apparent to those skilled in the art.

As a result of this invention it will be noted that an improved mining machine feeding mechanism is provided wherein the winding drums may be driven in winding direction either separately or simultaneously at a relatively slow cutting speed or at a relatively high machine moving speed, or rotated in unwinding direction under various degrees of frictionally controlled resistance or without such resistance. It will further be evident that an entirely separate plural speed transmission mechanism is provided between the motor and each of the winding drums, thereby enabling the drums to be driven and controlled entirely independently of each other. It will further be noted that the improved feeding mechanism is of an exceedingly compact and symmetrical design, the plural speed drive for each feed member being substantially identical in structure and therefore a substantial number of parts of the feed are duplicates and the cost of manufacture and replacement is thereby materially decreased.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining machine, a motor, cutting mechanism driven thereby including an elongated kerf cutter, and feeding mechanism driven by said motor including relatively rotatable feed operating and controlling members each adapted to cooperate with flexible feeding means and disposed on axes parallel to a vertical plane extending

transversely of the machine, and mechanism for driving said members in a direction to draw in said flexible feeding means either separately or simultaneously at a relatively 5 low cutting speed or at a relatively high machine moving speed including separate fast and slow speed gear trains for each of said members, and a plurality of manually controllable friction controlling clutches, one 10 individual to each gear train for each member, for controlling the connection of said members to their respective gear trains.

2. In a mining machine, a motor, cutting mechanism driven thereby including an 15 elongated kerf cutter, and feeding means driven by said motor including relatively rotatable feed operating and controlling members arranged on axes extending transversely of the machine and each adapted to 20 cooperate directly with flexible feeding means, and driving and controlling mechanism for said members including for each member a separate fast speed gear train and a slow speed gear train, and a plurality of 25 manually controllable friction controlling 30 clutches, one individual to each gear train for each member, for connecting said members to their respective gear trains to effect rotation thereof either separately or simultaneously at relatively slow speed or at relatively high speed.

3. In a mining machine, a motor, cutting mechanism driven thereby including an elongated kerf cutter, and feeding means driven 35 by said motor including relatively rotatable feed operating and controlling members arranged on axes extending transversely of the machine and each adapted to cooperate directly with flexible feeding means, and driving and controlling mechanism for said members including for each member a separate fast speed gear train and a slow speed gear train, and a plurality of manually controllable friction controlling clutches, one 40 individual to each gear train for each member, for connecting said members to their respective gear trains to effect rotation thereof either separately or simultaneously at relatively slow speed or at relatively high 45 speed or to permit rotation thereof under various degrees of frictional resistance.

4. In a mining machine, a motor, cutting mechanism driven thereby including an elongated kerf cutter, and feeding means driven 55 by said motor including relatively rotatable feed operating and controlling members arranged on axes extending transversely of the machine and each adapted to cooperate directly with flexible feeding 60 means, and driving and controlling mechanism for said members including for each member a separate fast speed gear train and a slow speed gear train, and a plurality of manually controllable friction controlling 65 clutches, one individual to each gear train

for each member, for connecting said members to their respective gear trains to effect rotation thereof either separately or simultaneously at relatively slow speed or at relatively high speed, or to permit rotation thereof under various degrees of frictional 70 resistance or without such resistance.

5. In a mining machine, a motor, cutting mechanism driven thereby including an elongated kerf cutter, and feeding means driven by said motor including relatively rotatable feed operating and controlling members disposed on axes extending transversely of the machine and each adapted to cooperate with flexible feeding means, and plural speed driving means for said members including separate fast and slow speed gear trains for each member, and a plurality of manually operable friction controlling clutches one individual to each gear train for each member. 75

6. In a mining machine, a motor, cutting mechanism driven thereby including an elongated kerf cutter, and feeding means driven by said motor including relatively rotatable feed operating and controlling members disposed on axes extending transversely of the machine and each adapted to cooperate with flexible feeding means, and plural speed transmission means between said motor and said members including a fast speed friction 80 controlling clutch and a slow speed friction controlling clutch for one member, and a fast speed friction controlling clutch and a slow speed friction controlling clutch for the other member whereby said members may be independently driven at either a relatively low speed or a relatively high speed. 90

7. In a mining machine, a motor, cutting mechanism driven thereby including an elongated kerf cutter, and feeding means driven by said motor including relatively rotatable feed operating and controlling members disposed on axes extending transversely of the machine and each adapted to cooperate with flexible feeding means, and plural speed transmission means between said motor and said members including a fast speed friction controlling clutch and a slow speed friction controlling clutch for one member, and a fast speed friction controlling clutch and a slow speed friction controlling clutch for the other member whereby said members may be driven in a direction to draw in said flexible feeding means either separately or simultaneously at a relatively slow cutting speed or at a relatively high machine moving speed. 100 105 110

8. In a mining machine, a motor, cutting mechanism driven thereby including an elongated kerf cutter, and feeding means driven by said motor including relatively rotatable feed operating and controlling members disposed on axes extending transversely of the machine and each adapted to cooperate with flexible feeding means, and plural speed transmission means between said motor and 125 130

- said members including a fast speed friction controlling clutch and a slow speed friction controlling clutch for one member, and a fast speed friction controlling clutch and a slow speed friction controlling clutch for the other member whereby said members may be driven in a direction to draw in said flexible feeding means either separately or simultaneously at a relatively slow cutting speed or at a relatively high machine moving speed or may rotate in a direction to pay out said flexible feeding means under various degrees of operator-controlled frictional resistance.
9. In a mining machine, a motor, cutting mechanism driven thereby including an elongated kerf cutter, and feeding means driven by said motor including relatively rotatable feed operating and controlling members disposed on axes extending transversely of the machine and each adapted to cooperate with flexible feeding means, and plural speed transmission means between said motor and said members including a fast speed friction controlling clutch and a slow speed friction controlling clutch for one member, and a fast speed friction controlling clutch and a slow speed friction controlling clutch for the other member whereby said members may be driven in a direction to draw in said flexible feeding means either separately or simultaneously at a relatively slow cutting speed or at a relatively high machine moving speed, or may rotate in a direction to pay out said flexible feeding means under various degrees of operator-controlled frictional resistance or may freely rotate in the paying out direction.
10. In a mining machine, a machine frame 40 slideable on its bottom on the mine floor, a motor carried by said frame, cutting mechanism driven by said motor including an elongated kerf cutter, and feeding means driven by said motor including relatively rotatable feed operating and controlling members each adapted to cooperate with flexible feeding means and arranged on axes extending transversely of the machine, and plural speed driving means for said members including separate fast and slow speed worm gear trains for one member and separate fast and slow speed worm gear trains for said other member whereby said members may be driven either separately or simultaneously in a direction to draw in said flexible feeding means at a relatively low speed or at a relatively high speed.
11. In a mining machine, a machine frame 45 slideable on its bottom on the mine floor, a motor carried by said frame, cutting mechanism driven by said motor including an elongated kerf cutter, and feeding means driven by said motor including relatively rotatable feed operating and controlling members each adapted to cooperate with flexible feeding means and arranged on axes extending transversely of the machine, and plural speed driving means for said members including separate fast and slow speed worm gear trains for one member and separate fast and slow speed worm gear trains for said other member whereby said members may be driven either separately or simultaneously in a direction to draw in said flexible feeding means at a relatively low speed or at a relatively high speed or may rotate in a direction to pay out said flexible feeding means under various degrees of frictional resistance.
12. In a mining machine, a machine frame 50 slideable on its bottom on the mine floor, a motor carried by said frame, cutting mechanism driven by said motor including an elongated kerf cutter, and feeding means driven by said motor including relatively rotatable feed operating and controlling members each adapted to cooperate with flexible feeding means and arranged on axes extending transversely of the machine, and plural speed driving means for said members including separate fast and slow speed worm gear trains for one member and separate fast and slow speed worm gear trains for said other member whereby said members may be driven either separately or simultaneously in a direction to draw in said flexible feeding means at a relatively low speed or at a relatively high speed or may rotate in a direction to pay out said flexible feeding means under various degrees of frictional resistance.
13. In a mining machine, a machine frame 55 slideable on its bottom on the mine floor, a motor carried by said frame, cutting mechanism driven by said motor including an elongated kerf cutter, and feeding means driven by said motor including relatively rotatable feed operating and controlling members each adapted to cooperate with flexible feeding means and arranged on axes extending transversely of the machine, and plural speed driving means for said members including separate fast and slow speed worm gear trains for one member and separate fast and slow speed worm gear trains for said other member whereby said members may be driven either separately or simultaneously in a direction to draw in said flexible feeding means at a relatively low speed or at a relatively high speed or may rotate in a direction to pay out said flexible feeding means under various degrees of frictional resistance.
14. In a mining machine, a machine frame 60 slideable on its bottom on the mine floor, a motor carried by said frame, cutting mechanism driven by said motor including an elongated kerf cutter, and feeding means driven by said motor including relatively rotatable feed operating and controlling members each adapted to cooperate with flexible feeding means and arranged on axes extending transversely of the machine, and plural speed driving means for said members including separate fast and slow speed worm gear trains for one member and

- separate fast and slow speed worm gear trains for said other member whereby said members may be independently driven at either a relatively high speed or at a relatively slow speed, each of said worm gear trains including a separate friction controlling clutch. 6 70
16. In a mining machine, a machine frame 10 slidable on its bottom on the mine floor, a motor carried by said frame, cutting mechanism driven by said motor including an elongated kerf cutter, and feeding means driven by said motor including relatively rotatable feed operating and controlling members each 15 adapted to cooperate with flexible feeding means and arranged on axes extending transversely of the machine, and plural speed driving means for said members including separate fast and slow speed worm gear trains 20 for one member and separate fast and slow speed worm gear trains for said other member whereby said members may be independently driven at either a relatively high speed or at a relatively slow speed, each of said 25 worm gear trains including a final worm wheel, said worm wheels being rotatable on axes extending transversely of the machine. 30
16. In a mining machine, a machine frame 35 slidable on its bottom on the mine floor, a motor carried by said frame, cutting mechanism driven by said motor including an elongated kerf cutter, and feeding means driven by said motor including relatively rotatable feed operating and controlling members each 40 adapted to cooperate with flexible feeding means and arranged on axes extending transversely of the machine, and plural speed driving means for said members including separate fast and slow speed worm gear trains for one 45 member and separate fast and slow speed worm gear trains for said other member whereby said members may be independently driven at either a relatively high speed or at a relatively slow speed, each of said worm gear trains including a final worm wheel, 50 said worm wheels being coaxially arranged and rotatable on axes extending transversely of the machine. 55
17. In a mining machine, a machine frame 60 slidable on its bottom on the mine floor, a motor carried by said frame, and cutting mechanism driven by said motor including the elongated kerf cutter, and feeding means driven by said motor including relatively rotatable feed operating and controlling members each 65 adapted to cooperate with flexible feeding means, and plural speed driving means for said members including separate fast and slow speed gear trains for each member, said 70 four gear trains including four final transmission gears coaxially arranged on axes extending transversely of the machine. 75
18. In a mining machine, a machine frame 80 slidable on its bottom on the mine floor, a motor carried by said frame, cutting mechanism driven by said motor including relatively rotatable feed operating and controlling members each 85 adapted to cooperate with flexible feeding means, and plural speed driving means for said members including separate fast and slow speed gear trains for each member, said four gear trains including four final transmission gears coaxially arranged on axes extending transversely of the machine, and a separate friction controlling clutch for each gear. 90
19. In a mining machine, a machine frame 95 slidable on its bottom on the mine floor, a motor carried by said frame, cutting mechanism driven by said motor including an elongated kerf cutter and feeding means driven by said motor including relatively rotatable feed operating and controlling members each adapted to cooperate with flexible feeding means and separate and distinct fast and slow speed transmission means for each member each including a horizontal drive shaft, said shafts being arranged in axial alinement, and driving connections between each of said shafts and its respective member. 100
20. In a mining machine, a machine frame 105 slidable on its bottom on the mine floor, a motor carried by said frame, cutting mechanism driven by said motor including an elongated kerf cutter, and feeding means driven by said motor including relatively rotatable feed operating and controlling members each 110 adapted to cooperate with flexible feeding means, and plural speed driving connections for each member including a fast speed gear train and a slow speed gear train for one member, and a fast speed gear train and a slow speed gear train for the other member, said trains including coaxial terminal gears, a shaft coaxial with each set of terminal gears, and a separate friction controlling clutch for connecting each terminal gear to its respective shaft. 115
21. In a mining machine, a machine frame 120 slidable on its bottom on the mine floor, a motor carried by said frame, cutting mechanism driven by said motor including an elongated kerf cutter, and feeding means driven by said motor including relatively rotatable feed operating and controlling members each 125 adapted to cooperate with flexible feeding means, and separate plural speed driving connections for each member including a fast speed gear train and a slow speed gear train, said gear trains each including a separate friction controlling clutch and said clutches being coaxially arranged, two of said friction clutches controlling the fast and slow speed drive for each member. 130
22. In a mining machine, a machine frame 135 slidable on its bottom on the mine floor, a motor carried by said frame, cutting mechanism driven by said motor including an

- elongated kerf cutter, and feeding means driven by said motor including relatively rotatable feed operating and controlling members each adapted to cooperate with flexible feeding means, and separate plural speed driving connections for each member including a fast speed gear train and a slow speed gear train, said gear trains each including a separate friction controlling clutch and said clutches being coaxially arranged and disposed on axes extending transversely of the machine, two of said friction clutches controlling the fast and slow speed drive for each member.
23. In a mining machine, a machine frame slidable on its bottom on the mine floor, a horizontal motor carried by said frame and having its power shaft extending longitudinally of the machine, cutting mechanism driven from one end of said motor including an elongated kerf cutter, and feeding means driven from the opposite end of said motor including relatively rotatable feed operating and controlling members each adapted to cooperate with flexible feeding means, and plural speed transmission connections for each member, the transmission connections for one member being separate and distinct from the transmission connections for the other member whereby said members may be independently driven at relatively slow and relatively high speeds.
24. In a mining machine, a machine frame slidable on its bottom on the mine floor, a horizontal motor carried by said frame and having its power shaft extending longitudinally of the machine, cutting mechanism driven from one end of said motor including an elongated kerf cutter, and feeding means driven from the opposite end of said motor including relatively rotatable feed operating and controlling members each adapted to cooperate with flexible feeding means, and plural speed transmission connections for each member, the transmission connections for one member being separate and distinct from the transmission connections for the other member and each transmission connection including a separate frictional controlling clutch whereby said members may be independently driven either separately or simultaneously.
25. In a mining machine, a machine frame slidable on its bottom on the mine floor, a horizontal motor carried by said frame and having its power shaft extending longitudinally of the machine, cutting mechanism driven from one end of said motor including an elongated kerf cutter, and feeding means driven from the opposite end of said motor including relatively rotatable feed operating and controlling members each adapted to cooperate with flexible feeding means, and plural speed transmission connections for each member, the transmission connec-

tions for one member being separate and distinct from the transmission connections for the other member, each transmission connection including a separate frictional controlling clutch whereby said members may be independently driven either separately or simultaneously or may rotate under various degrees of frictional resistance.

26. In a mining machine, machine feeding means including a feed operating member and a cooperating flexible feeding element and guiding means for guiding said element relative to said feed operating member including a guide sheave, a mounting for said sheave pivoted to swing about a horizontal axis, and a pivoted swing arm mounted on the machine and connected to said sheave mounting.

27. In a mining machine, machine feeding means including a machine feeding element and a cooperating flexible element and guiding means for guiding said flexible element relative to said feeding element including a guide sheave, normally disposed on a substantially vertical axis, and a horizontal pivotal mounting for said sheave having a passage through its pivotal axis through which said flexible element is adapted to extend into engagement with said sheave.

28. In a mining machine, machine feeding means including a machine feeding element and a cooperating flexible element and guiding means for guiding said flexible element relative to said feeding element including a guide sheave, a horizontally swingable support for said sheave mounted on the machine, said sheave being mounted on said support at the end thereof opposite from its pivot, and means arranged adjacent said sheave for locking said swingable support in one position.

29. A mining machine feeding mechanism including relatively rotatable feeding members each adapted to cooperate directly with flexible feeding means, and motor operated driving means for said members including a separate and distinct plural speed transmission mechanism for each member whereby said members may be rotated either separately or simultaneously at relatively high speed or at relatively low speed and including fast and slow speed terminal gears for each transmission mechanism, a terminal gear of one transmission mechanism being arranged coaxially with a terminal gear of said other mechanism, and manually controllable friction controlling clutches, one individual to each terminal gear, for connecting said members in driving relation with their respective terminal gears.

30. A mining machine feeding mechanism including relatively rotatable feeding members each adapted to cooperate directly with flexible feeding means, and motor operated driving means for said members including a

separate and distinct plural speed transmission mechanism for each member whereby said members may be rotated either separately or simultaneously at relatively high speed 5 or at relatively low speed and including fast and slow speed terminal gears for each transmission mechanism, said terminal gears for both transmission mechanisms being arranged in coaxial relation, and manually controllable friction controlling clutches, one individual to each terminal gear, for connecting said members in driving relation with their relation with their respective terminal gears.

31. A mining machine feeding mechanism 15 including relatively rotatable feeding members each adapted to cooperate directly with flexible feeding means, and motor operated driving means for said members including a separate and distinct plural speed transmission mechanism for each member whereby said members may be rotated either separately or simultaneously at relatively high speed or at relatively low speed, said transmission mechanisms including aligned shafts, driving connections between said shafts and said members respectively, a fast speed gear train and a slow speed gear train for each shaft having fast and slow speed terminal gears, and connections between said gears and their 20 respective shafts.

32. A mining machine feeding mechanism including relatively rotatable feeding members each adapted to cooperate directly with flexible feeding means, and motor operated 35 driving means for said members including a separate and distinct plural speed transmission mechanism for each member whereby said members may be rotated either separately or simultaneously at relatively high speed or at relatively low speed, said transmission mechanisms including aligned shafts, driving connections between said shafts and said members respectively, a fast speed gear train and a slow speed gear train for each shaft having fast and slow speed terminal gears arranged coaxially with their respective shafts, and connections between said 40 gears and their respective shafts.

33. A mining machine feeding mechanism 45 including relatively rotatable feeding members each adapted to cooperate directly with flexible feeding means, and motor operated driving means for said members including a separate and distinct plural speed transmission mechanism for each member whereby said members may be driven either separately or simultaneously at relatively high speed or at relatively low speed, said transmission mechanisms including aligned shafts, driving connections between said shafts and said members respectively, and a fast speed gear train and a slow speed gear train for each shaft.

34. A mining machine feeding mechanism

including relatively rotatable feeding members each adapted to cooperate directly with flexible feeding means, and motor operated driving means for said members including a separate and distinct plural speed transmission mechanism for each member whereby said members may be driven either separately or simultaneously at relatively high speed or at relatively low speed, said transmission mechanisms including aligned shafts, 70 driving connections between said shafts and said members respectively, and a fast speed gear train and a slow speed gear train for each shaft, said gear trains each having a terminal element coaxial with their respective shafts.

35. A mining machine feeding mechanism including relatively rotatable feeding members each adapted to cooperate directly with flexible feeding means, and motor operated 75 driving means for said members including a separate and distinct plural speed transmission mechanism for each member whereby said members may be driven either separately or simultaneously at relatively high speed or at relatively low speed, said transmission mechanisms including aligned shafts, driving connections between said shafts and said members respectively, a fast speed gear train and a slow speed gear train for each 80 shaft, said gear trains each having a terminal element coaxial with their respective shafts, and manually controllable clutches for connecting said terminal elements to their respective shafts.

36. A mining machine feeding mechanism including relatively rotatable feeding members each adapted to cooperate directly with flexible feeding means, and motor operated 85 driving means for said members including aligned shafts, driving connections between said feed members and their respective shafts, and a separate and distinct fast and slow speed worm gear train for each shaft.

37. A mining machine feeding mechanism 90 including relatively rotatable feeding members each adapted to cooperate directly with flexible feeding means, and motor operated driving means for said members including aligned shafts, driving connections between 95 said feed members and their respective shafts, and a separate and distinct fast and slow speed worm gear train for each shaft and including a fast speed worm wheel and a slow speed worm wheel coaxial with each shaft.

38. A mining machine feeding mechanism 100 including relatively rotatable feeding members each adapted to cooperate directly with flexible feeding means, and motor operated driving means for said members including aligned shafts, driving connections between 105 said feed members and their respective shafts, a fast and slow speed worm gear train for each shaft and including a fast speed worm wheel and a slow speed worm wheel coaxial 110

with each shaft, and manually controllable clutches for connecting said worm wheels to their respective shafts.

39. A mining machine feeding mechanism including relatively rotatable feeding members each adapted to cooperate directly with flexible feeding means, and motor operated driving means for said members whereby said members may be driven either separately or simultaneously at relatively high speed or at relatively low speed and including a shaft individual to each member, said shafts being arranged in axial alignment, fast and slow speed gear trains for each shaft, and selectively operable controlling clutches, one for each gear train coaxial with said shafts.

40. A mining machine feeding mechanism including relatively rotatable feeding members each adapted to cooperate directly with flexible feeding means, and motor operated driving means for said members including shafts, one individual to each member, said shafts being arranged in axial alignment, a fast speed gear train and a slow speed gear train for each shaft, and selectively operable friction controlling clutches for connecting said gear train to their respective shafts.

41. A mining machine feeding mechanism including relatively rotatable feeding members each adapted to cooperate directly with flexible feeding means, and motor operated driving means for said members including a separate and distinct plural speed transmission mechanism for each member whereby said members may be driven either separately or simultaneously at relatively high speed or at relatively low speed and including a separate and distinct fast and slow speed worm gear train for each member, one gear train for each member including a horizontal worm and a worm wheel meshing therewith.

42. A mining machine feeding mechanism including relatively rotatable feeding members each adapted to cooperate directly with flexible feeding means, and motor operated driving means for said members including a separate and distinct plural speed transmission mechanism for each member whereby said members may be driven either separately or simultaneously at relatively high speed or at relatively low speed, said transmission mechanisms including a separate and distinct fast and slow speed worm gear train for each member, one gear train for each member including a horizontal worm and a worm wheel meshing therewith and rotatable about a vertical axis.

43. A mining machine feeding mechanism including relatively rotatable feeding members each adapted to cooperate directly with flexible feeding means, and motor operated driving means for said members including a separate and distinct plural speed transmission mechanism for each member whereby said members may be driven either separately

or simultaneously at relatively high speed or at relatively low speed and including a separate and distinct fast and slow speed worm gear train for each member, one gear train for each member including a horizontal worm, a worm wheel meshing therewith, and a worm driven by said worm wheel.

44. A mining machine feeding mechanism including relatively rotatable feeding members each adapted to cooperate directly with flexible feeding means, and motor operated driving means for said members including a separate and distinct plural speed transmission mechanism for each member whereby said members may be driven either separately or simultaneously at relatively high speed or at relatively low speed, said transmission mechanisms including a separate and distinct fast and slow speed worm gear train for each member, one gear train for each member including a horizontal worm, a worm wheel meshing therewith and rotatable about a vertical axis, and a worm driven by said worm wheel.

45. A mining machine feeding mechanism including relatively rotatable feeding members each adapted to cooperate directly with flexible feeding means, and motor operated driving means for said members including a separate and distinct plural speed transmission mechanism for each member whereby said members may be driven either separately or simultaneously at relatively high speed or at relatively low speed, said transmission mechanisms including fast and slow speed gear trains for each member, one gear train for each member including a worm rotating on a horizontal axis, a worm wheel meshing therewith, the worm of one gear train being arranged parallel with the worm of the other gear train.

46. A mining machine feeding mechanism including relatively rotatable feeding members disposed with their axes parallel to a transverse vertical plane and each adapted to cooperate directly with flexible feeding means, and motor operated driving means for said members including a separate and distinct plural speed transmission mechanism for each member whereby said members may be driven either separately or simultaneously at relatively high speed or at relatively low speed, said transmission mechanisms including a fast speed gear train and a slow speed gear train for each member, the gear trains for each member each including a final terminal element, the terminal elements of the gear trains for both members having their axes arranged parallel to a common straight line.

47. A mining machine feeding mechanism including relatively rotatable feeding members disposed with their axes parallel to a transverse vertical plane and each adapted to cooperate directly with flexible feeding

means, and motor operated driving means for said members including a separate and distinct plural speed transmission mechanism for each member whereby said members may be driven either separately or simultaneously at relatively high speed or at relatively low speed, said transmission mechanism including a fast speed gear train and a slow speed gear train for each member, the gear trains for each member each including a final terminal element, the terminal elements of the gear trains for both members having their axes arranged parallel to a common straight line, and selectively operable clutches for connecting said members in driving relation with their respective terminal gears.

48. A mining machine feeding mechanism including relatively rotatable feeding members each adapted to cooperate directly with flexible feeding means, and motor operated driving means for said members whereby said members may be driven either separately or simultaneously at relatively high speed or at relatively low speed, including a separate and distinct plural speed transmission mechanism for each member, each transmission mechanism including worms rotating on angularly relaxed axes and a worm wheel meshing with each worm.

49. A mining machine feeding mechanism including relatively rotatable feeding members each adapted to cooperate directly with flexible feeding means, and motor operated driving means for said members whereby said members may be driven either separately or simultaneously at relatively high speed or at relatively low speed, including a separate and distinct plural speed transmission mechanism for each member, each transmission mechanism including worms rotating on angularly related axes and a worm wheel meshing with each worm and a manually controllable clutch for connecting the final worm wheel of each mechanism in driving relation with its respective feed member.

50. A mining machine feeding mechanism including relatively rotatable feeding members each adapted to cooperate directly with flexible feeding means, and motor operated driving means for said members whereby said members may be driven either separately or simultaneously at relatively high speed or at relatively low speed, including a separate and distinct plural speed transmission mechanism for each member, each transmission mechanism including worms rotating on angularly related axes, one of said worms being horizontally disposed, and a worm wheel meshing with each worm and a manually controllable clutch for connecting the final worm wheel of each mechanism in driving relation with its respective feed member.

51. In a mining machine, a machine frame adapted to rest upon and slide in any direction over the mine bottom, a motor carried

by said frame, cutting mechanism driven by said motor including an elongated kerf cutter projecting from said frame, and feeding means driven by said motor including relatively rotatable winding members of the same size and diameter and rotatable at like peripheral speeds both at a relatively fast predetermined moving speed and a relatively slow predetermined cutting speed and either capable of acting as a feed member and a controlling member, said winding members being disposed on horizontal transversely extending axes at the opposite sides of the longitudinal vertical center of the machine, one on the advancing side of the machine and the other on the receding side thereof, and each adapted to cooperate directly with flexible feeding means, and a separate and distinct plural speed transmission mechanism for each member, each transmission mechanism including a slow speed gear train and a fast speed gear train, and manually controllable clutch mechanism including a friction controlling clutch individual to each gear train for selectively connecting said gear trains in driving relation with their respective winding members.

52. In a mining machine, a machine frame adapted to rest upon and slide in any direction over the mine bottom, a motor carried by said frame, cutting mechanism driven by said motor including an elongated kerf cutter projecting from said frame, and feeding means driven by said motor including relatively rotatable winding members of the same size and diameter and rotatable at like peripheral speeds both at a relatively fast predetermined moving speed and a relatively slow predetermined cutting speed and either capable of acting as a feed member and a controlling member, said winding members being disposed on horizontal transverse axes at the opposite sides of the longitudinal vertical center of the machine, one on the advancing side on the machine and the other on the receding side thereof, and each adapted to cooperate directly with flexible feeding means, and mechanism for effecting rotation of said winding members in a direction to draw in their respective flexible feeding means either separately or simultaneously at relatively high speed or at relatively low speed including a separate and distinct fast and slow speed transmission gearing for each member, each gearing including a fast speed friction controlling clutch and a slow speed friction controlling clutch.

53. In a mining machine, a machine frame adapted to rest upon and slide in any direction over the mine bottom, a motor carried by said frame, cutting mechanism driven by said motor including an elongated kerf cutter projecting from said frame, and feeding means driven by said motor including

relatively rotatable winding members of the same size and diameter and rotatable at like peripheral speeds both at a relatively fast predetermined moving speed and a relatively slow predetermined cutting speed and either capable of acting as a feed member and a controlling member, said winding members being disposed on horizontal transverse axes at the opposite sides of the longitudinal vertical center of the machine, one on the advancing side on the machine and the other on the receding side thereof, and each adapted to cooperate directly with flexible feeding means, and mechanism for effecting rotation of said winding members in a direction to draw in their respective flexible feeding means either separately or simultaneously at relatively high speed or at relatively low speed, or to permit said winding members to revolve in a direction to pay out said flexible feeding means under various degrees of frictional resistance including a separate and distinct fast and slow speed transmission gearing for each member, each gearing including a fast speed friction controlling clutch and a slow speed friction controlling clutch.

54. In a mining machine, a machine frame adapted to rest upon and slide in any direction over the mine bottom, a motor carried by said frame, cutting mechanism driven by said motor including an elongated kerf-cutter projecting from said frame, and feeding means driven by said motor including relatively rotatable winding members of the same size and diameter and rotatable at like peripheral speeds both at a relatively fast predetermined moving speed and a relatively slow predetermined cutting speed and either capable of acting as a feed member and a controlling member, said winding members being disposed on horizontal transverse axes at the opposite sides of the longitudinal vertical center of the machine, one on the advancing side on the machine and the other on the receding side thereof, and each adapted to cooperate directly with flexible feeding means, and mechanism for effecting rotation of said winding members in a direction to draw in their respective flexible feeding means either separately or simultaneously at relatively high speed or at relatively low speed, or to permit said winding members to revolve in a direction to pay out said flexible feeding means under various degrees of frictional resistance or without such resistance including a separate and distinct fast and slow speed transmission gearing for each member, each gearing including a fast speed friction controlling clutch and a slow speed friction controlling clutch.

55. A mining machine feeding mechanism including relatively rotatable feeding members disposed with their axes parallel to a transverse vertical plane and each adapted

to cooperate directly with flexible feeding means, and motor operated driving means for said members including a fast speed gear train and a slow speed gear train individual to each member, each gear train having a friction controlling clutch, two friction clutches controlling each member. 70

56. A mining machine feeding mechanism including relatively rotatable feeding members disposed with their axes parallel to a transverse vertical plane and each adapted to cooperate directly with flexible feeding means, and motor operated driving means for said members including a fast speed gear train and a slow speed gear train individual to each member, each gear train having a friction controlling clutch, two friction clutches controlling each member, and said clutches being arranged on axes parallel to a common straight line. 75 80

57. A mining machine feeding mechanism including relatively rotatable feeding members disposed with their axes parallel to a transverse vertical plane and each adapted to cooperate directly with flexible feeding means, and motor operated driving means for said members including a fast speed gear train and a slow speed gear train individual to each member, each gear train having a friction controlling clutch, two friction clutches controlling each member and said clutches being arranged on axes parallel to a line parallel with the axes of said feed members. 90 95

58. A mining machine feeding mechanism including relatively rotatable feeding members each adapted to cooperate directly with flexible feeding means, and motor operated driving means for said members including a fast speed gear train and a slow speed gear train individual to each member, each gear train having a friction controlling clutch, two friction clutches controlling each member, and all of said clutches being coaxially arranged. 100 105

59. A mining machine feeding mechanism including relatively rotatable feeding members each adapted to cooperate directly with flexible feeding means, driving and controlling means for said members including a fast speed clutch and a slow speed clutch for each member, and mechanism for operating said clutches including an operating member for each set of clutches, aligned shafts, one connected with each operating member and means for separately rotating said shafts. 110 115

60. A mining machine feeding mechanism including relatively rotatable feeding members each adapted to cooperate directly with flexible feeding means, driving and controlling means for said members including a fast speed clutch and a slow speed clutch for each member, and mechanism for operating said clutches including an operating member for each set of clutches, aligned 120 125

shafts each having a threaded portion, a nut threadedly connected to the threaded portion of each shaft, connections between said nuts and said operating members for each set of clutches, and means for separately rotating said shafts to effect independent axial adjustment of said nuts.

61. A mining machine feeding mechanism including relatively rotatable feeding members each adapted to cooperate directly with flexible feeding means, driving and controlling means for said members including a fast speed clutch and a slow speed clutch for each member, and mechanism for operating said clutches including an operating member for each set of clutches, aligned hollow shafts, one connected to the operating member for each set of clutches, and means for separately rotating said shafts including an operating rod extending axially therethrough.

62. A mining machine feeding mechanism including relatively rotatable feeding members each adapted to cooperate directly with flexible feeding means, driving and controlling means for said members including a fast speed clutch and a slow speed clutch for each member, and mechanism for operating said clutches including an operating member for each set of clutches, aligned hollow shafts, one connected to the operating member for each set of clutches, and means for rotating said shafts including an operating rod extending axially therethrough and operating handles carried by the opposite ends of said rod.

63. A mining machine feeding mechanism including relatively rotatable feeding members each adapted to cooperate directly with flexible feeding means, driving and controlling means for said members including a fast speed clutch and a slow speed clutch for each member, and mechanism for operating said clutches including an operating member for each set of clutches, aligned hollow shafts, one connected to the operating member for each set of clutches, and means for separately rotating said shafts including an operating rod extending axially therethrough and connecting devices carried by the opposite ends of said rod for alternatively connecting said shafts to said rod.

64. A mining machine feeding mechanism including relatively rotatable feeding members each adapted to cooperate directly with flexible feeding means, driving and controlling means for said members including a fast speed clutch and a slow speed clutch for each member, and mechanism for operating said clutches including an operating member for each set of clutches, aligned hollow shafts, one connected to the operating member for each set of clutches, and means for separately rotating said shafts including an operating rod extending centrally therethrough and mounted for axial movement within said

shafts and clutch devices carried by the opposite ends of said rod and alternatively connectible to said shafts.

65. A mining machine feeding mechanism including relatively rotatable feed members each adapted to cooperate directly with flexible feeding means, and motor operated driving means for said members including a separate and distinct plural speed transmission mechanism for each member whereby said members may be driven either separately or simultaneously at relatively high speed or at relatively low speed, each of said transmission mechanisms including aligned gears, a slow speed gear train driven by one of said aligned gears and a fast speed gear train driven by said other gear.

66. A mining machine feeding mechanism including relatively rotatable feed members each adapted to cooperate directly with flexible feeding means, and motor operated driving means for said members including a separate and distinct plural speed transmission mechanism for each member whereby said members may be driven either separately or simultaneously at relatively high speed or at relatively low speed, each of said transmission mechanisms including aligned gears rotatable at the same angular speed, a slow speed gear train driven by one of said aligned gears and a fast speed gear train driven by said other gear.

67. A mining machine feeding mechanism including relatively rotatable feed members each adapted to cooperate directly with flexible feeding means, and motor operated driving means for said members including a separate and distinct plural speed transmission mechanism for each member whereby said members may be driven either separately or simultaneously at relatively high speed or at relatively low speed, each of said transmission mechanisms including aligned gears rotating with their axes disposed in a vertical plane extending longitudinally of the machine, a slow speed gear train driven by one of said aligned gears and a fast speed gear train driven by said other gear.

68. A mining machine feeding mechanism including relatively rotatable feed members each adapted to cooperate directly with flexible feeding means, and motor operated driving means for said members including a separate and distinct plural speed transmission mechanism for each member whereby said members may be driven either separately or simultaneously at relatively high speed or at relatively low speed, each of said transmission mechanisms including aligned gears rotatable on horizontal axes, a slow speed gear train driven by one of said aligned gears and a fast speed gear train driven by said other gear.

69. A mining machine feeding mechanism

including relatively rotatable feed members each adapted to cooperate directly with flexible feeding means, and motor operated driving means for said members including a separate and distinct plural speed transmission mechanism for each member whereby said members may be driven either separately or simultaneously at relatively high speed or at relatively low speed, each of said transmission mechanisms including aligned gears rotatable on horizontal axes extending longitudinally of the machine, a slow speed gear train driven by one of said aligned gears and a fast speed gear train driven by said other gear.

70. A mining machine feeding mechanism including relatively rotatable feed members each adapted to cooperate directly with flexible feeding means, and motor operated driving means for said members including a separate and distinct plural speed transmission mechanism for each member whereby said members may be driven either separately or simultaneously at relatively high speed or at relatively low speed, each of said transmission mechanisms including aligned worms, a slow speed gear train including a worm wheel meshing with one of said aligned worms and a fast speed gear train including a worm wheel meshing with said other worm.

71. In a mining machine, a machine frame adapted to rest upon and slide in any direction over the mine bottom, a centrally located motor carried by said frame and having its power shaft horizontally disposed and extending longitudinally of the machine, kerf cutting mechanism driven from one end of said power shaft and including an elongated kerf cutter projecting from the forward end of said frame, and feeding means driven from the opposite end of said power shaft including relatively rotatable winding members, said winding members being disposed on horizontal transversely extending axes at the opposite sides of the longitudinal median line of the machine, one on the advancing side of the machine and the other on the receding side thereof, said members being disposed at the rear end of the machine remote from the end from which said kerf cutter projects and each adapted to cooperate directly with flexible feeding means, and a separate and distinct plural speed transmission mechanism for each member for rotating said members either separately or simultaneously in a direction to draw in their respective flexible feeding means at relatively high speed or at relatively low speed.

72. In a mining machine, a machine frame adapted to rest upon and slide in any direction over the mine bottom, a centrally located motor carried by said frame and having its power shaft horizontally disposed and extending longitudinally of the machine, kerf cutting mechanism driven from one end of

said power shaft and including an elongated kerf cutter projecting from the forward end of said frame, and feeding means driven from the opposite end of said power shaft including relatively rotatable winding members of the same size and diameter and rotatable at like peripheral speeds, said winding members being disposed on horizontal transversely extending axes at the opposite sides of the longitudinal median line of the machine, one on the advancing side of the machine and the other on the receding side thereof, said members being disposed at the rear end of the machine remote from the end from which said kerf cutter projects and each adapted to cooperate directly with flexible feeding means, and a separate and distinct plural speed transmission mechanism for each member for rotating said members either separately or simultaneously in a direction to draw in their respective flexible feeding means at relatively high speed or at relatively low speed.

73. In a mining machine, a machine frame adapted to rest upon and slide in any direction over the mine bottom, a centrally located motor carried by said frame and having its power shaft horizontally disposed and extending longitudinally of the machine, kerf cutting mechanism driven from one end of said power shaft and including an elongated kerf cutter projecting from the forward end of said frame, and feeding means driven from the opposite end of said power shaft including relatively rotatable winding members of the same size and diameter and rotatable at like peripheral speeds, said winding members being disposed on horizontal transversely extending axes at the opposite sides of the longitudinal median line of the machine, one on the advancing side of the machine and the other on the receding side thereof, said members being disposed at the rear end of the machine remote from the end from which said kerf cutter projects and each adapted to cooperate directly with flexible feeding means, and a separate and distinct plural speed transmission mechanism for each member for rotating said members either separately or simultaneously in a direction to draw in their respective flexible feeding means at relatively high speed or at relatively low speed, each transmission mechanism including a slow speed gear train and a fast speed gear train and manually controllable clutch mechanism for selectively connecting said gear trains in driving relation with their respective winding members.

74. In a mining machine, a machine frame adapted to rest upon and slide in any direction over the mine bottom, a centrally located motor carried by said frame and having its power shaft horizontally disposed and extending longitudinally of the machine, kerf cutting mechanism driven from one end of said power shaft and including an elongated

kerf cutter projecting from the forward end of said frame, and feeding means driven from the opposite end of said power shaft including relatively rotatable winding members of the same size and diameter and rotatable at like peripheral speeds, said winding members being disposed on horizontal transversely extending axes at the opposite sides of the longitudinal median line of the machine, one on the advancing side of the machine and the other on the receding side thereof, said members being disposed at the rear end of the machine remote from the end from which said kerf cutter projects and each adapted to cooperate directly with flexible feeding means, and a separate and distinct plural speed transmission mechanism for each member for rotating said members either separately or simultaneously in a direction to draw in their respective flexible feeding means at relatively high speed or at relatively low speed, each transmission mechanism including a slow speed gear train and a fast speed gear train and manually controllable clutch mechanism for selectively connecting said gear trains in driving relation with their respective winding members, or to permit said winding members to revolve in a direction to pay out said flexible feeding means under various degrees of frictional resistance.

75. In a mining machine, a machine frame adapted to rest upon and slide in any direction over the mine bottom, a centrally located motor carried by said frame and having its power shaft horizontally disposed and extending longitudinally of the machine, kerf cutting mechanism driven from one end of said power shaft and including an elongated kerf cutter projecting from the forward end of said frame, and feeding means driven from the opposite end of said power shaft including relatively rotatable winding members of the same size and diameter and rotatable at like peripheral speeds, said winding members being disposed on horizontal transversely extending axes at the opposite sides of the longitudinal median line of the machine, one on the advancing side of the machine and the other on the receding side thereof, said members being disposed at the rear end of the machine remote from the end from which said kerf cutter projects and each adapted to cooperate directly with flexible feeding means, and a separate and distinct plural speed transmission mechanism for each member for rotating said members either separately or simultaneously in a direction to draw in their respectively flexible feeding means at relatively high speed or at relatively low speed, each transmission mechanism including a slow speed gear train and a fast speed gear train and manually controllable clutch mechanism for selectively connecting said gear trains in driving relation with their respective winding members, or to permit said

winding members to revolve in a direction to pay out said flexible feeding means under various degrees of frictional resistance or without such resistance.

76. In a mining machine, a machine frame adapted to rest upon and slide in any direction over the mine bottom, a centrally located motor carried by said frame and having its power shaft horizontally disposed and extending longitudinally of the machine, kerf cutting mechanism driven from the forward end of said power shaft and including an elongated kerf cutter projecting from the forward end of said frame, and feeding means driven from the rear end of said power shaft and including relatively rotatable winding members arranged in coaxial relation and disposed at the rear end of the machine and each adapted to cooperate directly with flexible feeding means, and a separate and distinct plural speed transmission mechanism for each member for rotating said members either separately or simultaneously in a direction to draw in their respective flexible feeding means at relatively high speed or at relatively low speed.

77. In a mining machine, a machine frame adapted to rest upon and slide in any direction over the mine bottom, a centrally located motor carried by said frame and having its power shaft horizontally disposed and extending longitudinally of the machine, kerf cutting mechanism driven from the forward end of said power shaft and including an elongated kerf cutter projecting from the forward end of said frame, and feeding means driven from the rear end of said power shaft and including relatively rotatable winding members of the same size and diameter and rotatable at like peripheral speeds and arranged in coaxial relation and disposed at the rear end of the machine and each adapted to cooperate directly with flexible feeding means, and a separate and distinct plural speed transmission mechanism for each member for rotating said members either separately or simultaneously in a direction to draw in their respective flexible feeding means at relatively high speed or at relatively low speed. 95 100 105 110 115

78. A mining machine feeding mechanism including relatively rotatable feeding members each adapted to cooperate directly with flexible feeding means, and motor operated driving means for said members including aligned shafts one connected to each member, and a separate and distinct fast and slow speed transmission mechanism for each shaft. 120

79. A mining machine feeding mechanism including relatively rotatable feeding members each adapted to cooperate directly with flexible feeding means, driving and controlling means for said members including a fast speed clutch and a slow speed clutch for each member, and mechanism for independently 130

operating said clutches including a control element common to all of said clutches.

80. A mining machine feeding mechanism including relatively rotatable feeding members each adapted to cooperate directly with flexible feeding means, driving and controlling means for said members including a fast speed clutch and a slow speed clutch for each member, and mechanism for independently operating said clutches including a control element common to all of said clutches, and shiftable into one position for controlling the clutches for one member and in another position for controlling the clutches of said other member.

81. In a mining machine, machine feeding means including a machine feeding element and a cooperating flexible element, and guiding means for guiding said flexible element relative to said feeding element including a guide sheave rotatable about a substantially vertical axis for guiding said flexible element laterally from the machine, and a mounting for said guide sheave pivoted to turn about a horizontal axis extending longitudinally of the machine.

82. In a mining machine, machine feeding means including a machine feeding element and a cooperating flexible element, and guiding means for guiding said flexible element relative to said feeding element including a guide sheave, a support swingable about the axis of said sheave, and a second guide sheave carried at the end of said support remote from its pivot and adjustable therewith into predetermined positions to guide said flexible element laterally relative to the machine in opposite directions.

83. In a mining machine, machine feeding means including a machine feeding element and a cooperating flexible element, and guiding means for guiding said flexible element relative to said feeding element including a guide sheave, and a mounting for said sheave including a support element pivoted to turn about an axis extending longitudinally of the machine and said mounting having a passage through its pivotal axis through which said flexible element is adapted to extend into engagement with said sheave.

84. In a mining machine, machine feeding means including a machine feeding element and a cooperating flexible element, and guiding means for guiding said flexible element relative to said feeding element including an arm pivoted to swing about a horizontal axis, a support pivotally mounted on the end of said arm remote from its pivot to swing about an axis parallel to said arm axis, and a guide sheave carried by said pivoted support.

85. In mining machine, machine feeding means including a machine feeding element and a cooperating flexible element, and guiding means for guiding said flexible element relative to said feeding element including an

arm pivoted to swing about a horizontal axis, a support pivotally mounted on the end of said arm remote from its pivot to swing about an axis parallel to said arm axis, and a guide sheave carried by said pivoted support, said support having a passage through its pivotal axis through which said flexible element is adapted to extend into engagement with said sheave.

86. In a mining machine, feeding mechanism including relatively rotatable feeding members of the same size and diameter and rotatable at like peripheral speeds both at a relatively fast predetermined moving speed and a relatively slow predetermined cutting speed and each adapted to cooperate directly with flexible feeding means and either capable of acting as a feed member and a controlling member, motor operated devices for driving said members either separately or simultaneously in a direction to draw in their respective flexible feeding means at a relatively high speed or at a relatively low speed and including for each member a fast and slow speed transmission mechanism through which it, but not the other member, is driven, and truck driving mechanism driven from an element of one of said transmission mechanisms and operable wholly independently of said members.

87. In a mining machine, a motor, feeding mechanism driven from said motor and including relatively rotatable feeding members of the same size and diameter and rotatable at like peripheral speeds both at a relatively fast predetermined moving speed and a relatively slow predetermined cutting speed and each adapted to cooperate directly with flexible feeding means and either capable of acting as a feed member and a controlling member, motor operated devices for driving said members either separately or simultaneously in a direction to draw in their respective flexible feeding means at relatively high speed or at relatively low speed and including for each member a fast and slow speed transmission mechanism through which it, but not the other member, is driven, and truck driving mechanism driven from the same end of said motor as said feeding mechanism and through one of said transmission mechanisms and operable wholly independently of said members.

88. In a mining machine, feeding mechanism including relatively rotatable feeding members each adapted to cooperate directly with flexible feeding means, motor operated devices for driving said members either separately or simultaneously in a direction to draw in their respective flexible feeding means at relatively high speed or at relatively low speed and including a motor having a power shaft and a longitudinally extending transmission shaft driven by said motor power shaft, and truck driving mechanism driven by said transmission shaft and operable wholly independently of said members.

89. A mining machine feeding mechanism including relatively rotatable feed operating and controlling members each adapted to cooperate directly with flexible feeding means and arranged with their axes parallel to a transverse vertical plane, said members being of the same size and diameter and rotatable at the same peripheral speeds both at a relatively fast predetermined moving speed and a relatively slow predetermined cutting speed and either capable of acting as a feed member and a controlling member, and motor operated devices for driving said members either separately or simultaneously at relatively low speed or at relatively high speed including for each member fast and slow speed transmission mechanism through which it, but not the other member, is driven, each transmission mechanism including a fast speed worm gear train and a slow speed worm gear train.

90. A mining machine feeding mechanism including relatively rotatable feed operating and controlling members each adapted to cooperate directly with flexible feeding means and arranged with their axes horizontal and extending transversely of the machine, said members being of the same size and diameter and rotatable at the same peripheral speeds both at a relatively fast predetermined moving speed and a relatively slow predetermined cutting speed and either capable of acting as a feed member and a controlling member, and motor operated devices for driving said members either separately or simultaneously at relatively low speed or at relatively high speed including for each member fast and slow speed transmission mechanism through which it, but not the other member, is driven, each transmission mechanism including a fast speed friction controlling clutch and a slow speed friction controlling clutch.

91. A mining machine feeding mechanism including relatively rotatable feed operating and controlling members each adapted to cooperate directly with flexible feeding means and rotatable at like peripheral speeds both at a relatively fast predetermined moving speed and a relatively slow predetermined cutting speed, said members being arranged with their axes parallel to a transverse vertical plane and either capable of acting as a feed member and a controlling member, and motor operated devices for driving said members either separately or simultaneously at a relatively low predetermined speed or at a relatively high predetermined speed including for each member fast and slow predetermined speed transmission mechanism through which it, but not the other member, is driven, each transmission mechanism including coaxial fast and slow speed terminal gears.

92. A mining machine feeding mechanism including relatively rotatable feed operating and controlling members each adapted to co-

operate directly with flexible feeding means and rotatable at like peripheral speeds both at a relatively fast predetermined moving speed and a relatively slow predetermined cutting speed, said members being arranged with their axes horizontal and extending transversely of the machine and either capable of acting as a feed member and a controlling member, and motor operated devices for driving said members either separately or simultaneously at a relatively low predetermined speed or at a relatively high predetermined speed including for each member fast and slow predetermined speed transmission mechanism through which it, but not the other member, is driven, each transmission mechanism including coaxial fast and slow speed terminal gears and a friction controlling clutch individual to each gear.

93. A mining machine feeding mechanism including relatively rotatable feeding members each adapted to cooperate directly with flexible feeding means, and motor operated driving means for said members including for each member a plural predetermined speed transmission through which it, but not the other member, is driven, said transmission mechanisms being arranged generally on axes parallel to the axes of said feed members and each including a fast predetermined speed gear train and a slow predetermined speed train and a plurality of clutches, one individual to each gear train, for selectively connecting said trains in driving relation with their respective feeding members.

94. In a mining machine feeding mechanism, relatively rotatable feeding members disposed with their axes parallel to a transverse vertical plane and each adapted to cooperate directly with flexible feeding means, and motor operated devices for driving said members either separately or simultaneously in a direction to draw in their respective flexible feeding means at relatively high speed or at relatively low speed including a separate and distinct plural speed transmission mechanism for each member, each transmission mechanism including a longitudinally extending shaft, a fast speed gear train, and a slow speed gear train, each gear train including a terminal gear coaxial with said shaft.

95. In a mining machine feeding mechanism, relatively rotatable feeding members each adapted to cooperate directly with flexible feeding means, and motor operated devices for driving said members either separately or simultaneously in a direction to draw in their respective flexible feeding means at relatively high speed or at relatively low speed including aligned shafts one connected to each member, and a separate and distinct plural speed transmission mechanism for each shaft, each transmission mechanism including a longitudinally extending shaft,

a fast speed gear train, and a slow speed gear train, each gear train including a terminal gear coaxial with said longitudinal shaft.

96. In a mining machine feeding mechanism, relatively rotatable feeding members each adapted to cooperate directly with flexible feeding means, and motor operated devices for driving said members either separately or simultaneously in a direction to draw in their respective flexible feeding means at relatively high speed or at relatively low speed including aligned horizontal shafts one connected to each member and a separate and distinct plural speed transmission mechanism for each shaft, each transmission mechanism including a longitudinally extending shaft, a fast speed gear train, and a slow speed gear train, each gear train including a terminal gear coaxial with said longitudinal shaft.

97. In a mining machine feeding mechanism, relatively rotatable feeding members each adapted to cooperate directly with flexible feeding means, and motor operated devices for driving said members either separately or simultaneously in a direction to draw in their respective flexible feeding means at relatively high speed or at relatively low speed including aligned horizontal transversely extending shafts one connected to each member and a separate and distinct plural speed transmission mechanism for each shaft, each transmission mechanism including a longitudinally extending shaft, a fast speed gear train, and a slow speed gear train, each gear train including a terminal gear coaxial with said longitudinal shaft.

98. In a mining machine, a motor and feeding means driven by said motor including relatively rotatable feed operating and controlling members disposed on axes parallel to a transverse vertical plane and each adapted to cooperate with flexible feeding means, and separate fast and slow speed driving connections between said motor and each of said members entirely distinct from the drive for the other member including parallel worms and coaxial worm wheels meshing therewith.

99. In a mining machine, a motor and feeding means driven by said motor including relatively rotatable feed operating and controlling members disposed on axes parallel to a transverse vertical plane and each adapted to cooperate with flexible feeding means, separate fast and slow speed driving connections between said motor and each of said members entirely distinct from the drive for the other member including parallel worms and coaxial worm wheels meshing therewith, and a separate friction controlling clutch for connecting each worm wheel in driving relation with its respective member.

100. A mining machine feeding mechanism including relatively rotatable feed members disposed on axes parallel to a trans-

verse vertical plane and each adapted to cooperate directly with flexible feeding means, and motor operated driving means for said members including a fast speed gear train and a slow speed gear train for one member, a separate and distinct fast speed gear train and a slow speed gear train for said other member, the fast speed gear trains for both members including driving gears rotatable about parallel axes and the slow speed gear trains for both members including driving gears rotatable about parallel axes.

101. In a mining machine, cutting mechanism including a kerf cutter and driving means therefor including a motor shaft and a transmission element driven thereby, and feeding means including relatively rotatable feed operating and controlling members of the same size and diameter and rotatable at like peripheral speeds both at a relatively fast predetermined moving speed and a relatively slow predetermined cutting speed and either capable of acting as a feed member and a controlling member, said members each being adapted to cooperate directly with flexible feeding means, and motor operated driving means for said members for driving said members either separately or simultaneously in a direction to draw in their respective flexible feeding means at a relatively high predetermined speed or at a relatively low predetermined speed, and including for each member fast and slow predetermined speed transmission mechanism through which it, but not the other member, is driven and each transmission mechanism including a fast and slow speed gear trains and friction controlling clutches one individual to each gear train.

In testimony whereof I affix my signature.
MORRIS P. HOLMES.

CERTIFICATE OF CORRECTION.

Patent No. 1,875,335.

September 6, 1932.

MORRIS P. HOLMES.

It is hereby certified that error appears in the printed specification of the above numbered patent requiring correction as follows: Page 7, line 102, claim 6, for "ralatively" read relatively; page 8, line 19, claim 9, for the syllable "pose" read posed; page 9, line 52, claim 17, for "the" read an; page 10, line 89, claim 27, strike out the comma after "sheaves"; page 11, lines 12 and 13, claim 30, strike out the words "with their relation"; page 12, line 16, claim 39, after "train" insert a comma; and line 27, claim 40, for "train" read trains; page 13, line 7, claim 47, for "mechanism" read mechanisms; page 19, line 97, claim 93, after "speed" insert gear; and page 20, line 101, claim 101, strike out the article "a"; and that the said Letters Patent should be read with these corrections therein that the same may conform to the record of the case in the Patent Office.

Signed and sealed this 30th day of October, A. D. 1934.

Leslie Frazer

(Seal)

Acting Commissioner of Patents.
